UNITED STATES PATENT OFFICE.

HERBERT E. SHOOP, OF PITTSBURGH, PENNSYLVANIA.

TOBACCO PIPE.

Application filed November 14, 1925. Serial No. 69,018.

The object which I have in view is the provision of a tobacco pipe which will afford a clean, sweet and dry smoke, which will prevent nicotine traveling to the mouth-piece of the pipe, and which may be thoroughly cleaned when necessary in an expeditious and convenient manner.

A leading characteristic of my improved pipe is the provision of a well in the stem which preferably approaches the vertical but is somewhat rearwardly inclined to the lower portion of which is connected the bowl while the upper portion of the well is connected to the bit or mouth-piece. Within the well is removably mounted a plug which forms with the interior wall of the well a passage for the upward travel of the smoke towards the bit. This passage is preferably tortuous, and I prefer to form the same by means of a helical groove cut in the surface of the plug. The plug may be removed from the well by endwise movement.

The bowl is preferably provided with an upper, removable false bowl portion whose bottom is perforated for the downward escape of the smoke into a chamber formed in the base bowl and which chamber is connected to the lower portion of the well.

The base bowl is preferably provided with a flat bottom so that the pipe may stand upright when not in use.

Other novel features of construction and also of arrangement of parts will appear from the following description.

In the accompanying drawings, wherein I have illustrated the best embodiment of the principles of my invention now known to me, Fig. 1 is a side elevation of the pipe; Fig. 2 is a vertical section of the same; Fig. 3 is a plan view of the false bowl; Fig. 4 is a plan view of the pipe with the false bowl removed, and Fig. 5 is an elevation of the plug shown removed from its well.

Referring to the drawings A represents the base bowl which is interiorly threaded at its top as shown at 1 to receive the annular and threaded portion 2 of the false bowl B. The bottom of the false bowl is downwardly convexed and provided with perforations 3 for the downward escape of the smoke into the chamber 4 of the base bowl A.

The chamber 4 is connected by a passage 5 leading preferably from a point somewhat above the bottom of the chamber into the lower portion of a well C which is formed

in the stem 6 of the pipe, and which is preferably somewhat rearwardly inclined as shown.

The stem and base bowl of the pipe may be integral and formed of any suitable material, such as wood or composition, and the false bowl B may be formed also of any suitable material, but preferably of a composition. By employing a composition such as "bakelite", the body of the pipe may be molded in one piece while the material is in a plastic state, thus reducing cost and providing a durable structure. By forming the bowl and stem of transparent or translucent material the operation of the pipe and the spiral travel of the smoke about the plug is made visible to the smoker, thus adding greatly to the attractiveness of the pipe.

The well C is opened at least at one end 75 and preferably at both ends. Near its upper end the well is in communication with the passage 7 of the bit or mouth-piece D which may be integral with the stem or detachably connected thereto as is common in 80 smoking pipes. The stem and well should be of sufficient length to provide for cooling the smoke before it reaches the mouth-piece and also to drop the bowl to give the pipe the proper hang or balance and to 85 position the bowl sufficiently distant from the smoker's face.

E represents a plug, which may be of any suitable material, such as metal or hard rubber, and which is adapted to be inserted 90 into and fit snugly in the well C. I prefer to taper the walls of the well and the plug upwardly so that by inserting the plug from below into the well it may be caused to be held therein against accidental displacement. The lower end of the plug may be provided with a screw driver slot 8 so that it may be turned to loosen it to expedite its removal.

Means are provided between the interior 100 wall of the well and the plug for the upward travel of the smoke from the entrance passage 5 to the exit passage 7. This upward travel of the smoke is preferably in a tortuous path. Thus I have shown the surface of the plug E provided with a helical groove 9, which when the plug is in position in the well coacts with the wall of the well to form a helical passage for the ascent of the smoke. The ends of the plug are un- 110

grooved so as to close the ends of the well against the escape of smoke or the material entrance of air. At the lower end of the thread 9 the plug is provided with an annular groove 9^a which forms a bottom trap into which such saliva as may enter the well may be collected below the passage 5.

It is evident that the accumulation of moisture or foreign matter in the chamber 4 of the base bowl may be readily removed by first removing the false bowl.

It is further evident that the passages 5 and 7 are readily accessible for cleaning when the plug E is removed.

15 It is also evident that by removing the plug E its grooved surface is open for convenient cleaning and also the walls of the well may be readily wiped.

It is thus apparent that my pipe may be 20 readily and conveniently kept clean, thus insuring a sweet and dry smoke to the user. The upward passage of the smoke in the well also serves to cool the same as the helical passage thus formed has an effective 25 length many times the actual length of the well. Thus the smoker will not experience the biting of the tongue which is so frequently incident to pipe smoking.

What I desire to claim is:—

30 1. In a smoking pipe, the combination of a bowl, a stem containing a well which is open at both ends, a passage connecting the lower portion of said bowl with the lower portion of the well, a mouth-piece connected 35 with the upper portion of the stem and having its passage connected to the upper portion of the well, a removable tapering plug removably inserted in said well, a helical groove on the plug forming a passage for 40 the upward travel of the smoke and the ends of the well being closed by the end portions of the plug when the plug is in place, and a deposit chamber being provided in the well by the termination of said groove be-

low the mouth of the first mentioned passage. 45

2. In a smoking pipe, the combination of a bowl, a stem containing a well which is open at both ends, a passage connecting the lower portion of said bowl with the lower 50 portion of the well, a mouth-piece connected with the upper portion of the stem and having its passage connected to the upper portion of the well, a removable tapering plug removably inserted in said well, the ends of the well being closed by the end portions of the plug when the plug is in place, said plug having its greatest diameter at the lower end 55 thereof, a spiral passage for the upward travel of the smoke being provided on the 60 plug and the ends of the well being closed when the plug is in place, and an annular deposit chamber being provided on the plug by the termination of the spiral passage 65 above the lower closed end of the well and between the well and the plug below the mouth of the first mentioned passage.

3. In a smoking pipe, the combination of a base-bowl, a false bowl detachably mounted thereon, the bottom of said false bowl 70 being perforated and a chamber being provided within the base-bowl beneath the false bowl, a stem provided with a well which is open at both ends, a passage connecting said chamber to the lower end of said well, a 75 mouth piece connected to the upper end of said well, and a removable tapering plug in said well, the ends of the well being closed by the end portions of the plug, said plug having its greatest diameter at the lower end 80 thereof, a spiral passage for the upward travel of the smoke being provided on said plug and between the well and the plug, and an annular deposit chamber formed by the 85 termination of said spiral passage. 85

Signed at Pittsburgh, Pa., this 12th day of November, 1925.

HERBERT E. SHOOP.
